UNITED STATES PATENT OFFICE.

ARTHUR COULOMBE, OF NEW BEDFORD, MASSACHUSETTS.

RAILWAY-SWITCH.

1,032,815.

Specification of Letters Patent. Patented July 16, 1912.

Application filed August 24, 1911. Serial No. 645,705.

To all whom it may concern:

Be it known that I, ARTHUR COULOMBE, a subject of the King of Great Britain, and a resident of New Bedford, in the county of 5 Bristol and State of Massachusetts, have invented a new and Improved Railway-Switch, of which the following is a full, clear, and exact description.

My invention relates to railway switches, 10 and it has for its object to provide one having a rock shaft extending longitudinally of the main tracks, with two arms secured to the rock shaft, one of the arms having means for operating the switch rail, and the 15 other arm having means by which it is adapted to be operated by an adjustable member on a car.

Additional objects of my invention will 20 appear in the following complete specification, in which the preferred form of the invention is disclosed.

In the drawings similar characters of reference indicate corresponding parts in all the views, in which—

25 Figure 1 is a sectional longitudinal elevation showing my improvement; Fig. 2 is a plan view of Fig. 1; Fig. 3 is a transverse sectional view of Fig. 1, showing the means for rocking the shaft; and Fig. 4 30 is a transverse sectional view of Fig. 1, showing how the rock shaft is adapted to operate the switch rail.

By referring to the drawings it will be 35 seen that in bearings in a tube 5 there is journalized a rock shaft, 6, the tube 5 being preferably disposed in the road bed beneath the ties 7 to which the main rails 8 are secured. Arms 9 and 10 are secured to the rock shaft 5. To the arm 10 there is articulated a link 11, this link 11 being secured to a pin 12, this pin being secured to the switch rail 13, which is disposed for moving laterally on a seat 14, there being a slot 15 in the said seat through which the pin 12 is 45 disposed. The other arm 9 is articulated to a pin 16, which is disposed through a slot 17, in a seat 18, on which a lever 19 is disposed, the lever 19 being pivoted at one end at 20, and to the other end the pin 16 50 is secured. A tapering guide 21 is provided, which leads to the lever 19, at its pivoted end 20. On the car 22 there is a lever 23, at the lower terminal of which there is journalized a wheel 24, and when the motorman 55 on the car is desirous of throwing the switch rail 13 he operates the lever 23 so

that the wheel 24 will be disposed either to the right or to the left of the guide 21, and as the car advances the wheel 24 will be disposed between one of the sides 25 of the 60 seat 18 and one of the sides of the lever 19, so that the wheel 24 will move the lever 19 which by means of the arm 9 will rock the shaft 5 rocking the arm 10, and operating the link 11 to move the switch rail 13 in the 65 manner indicated.

Having thus described my invention, I claim as new and desire to secure by Letters Patent:

1. In a railway switch a main rail, a seat 70 disposed at the side of the main rail and below the horizontal plane at the top of the main rail, there being a slot in the bottom of the seat, a switch rail disposed for moving in the seat, a pin on the switch rail extending in the slot, a rock shaft, an arm on the rock shaft, a link secured at one end to the pin below the seat and articulated at its other end to the arm, a second seat disposed below the horizontal plane at the top 75 of the main rail and having a slot and sides extending upwardly substantially to the horizontal plane at the top of the main rail, a tapering guide secured to the seat between the sides thereof, a lever pivoted to 80 the seat between the sides, and forming a continuation of the tapering guide, a pin secured to the lever and disposed in the last-mentioned slot, and an arm secured to the rock shaft, and articulated to the last-men- 85 tioned pin.

2. In a railway switch a main rail, a seat disposed at the side of the main rail and below the horizontal plane at the top of the main rail; there being a slot in the bottom 95 of the seat, a switch rail disposed for moving in the seat, a pin on the switch rail extending in the slot, a rock shaft, an arm on the rock shaft, a link secured at one end to the pin below the seat and articulated at its other end to the arm, a second seat disposed below the horizontal plane at the top of the main rail and having a slot and sides extending upwardly substantially to the horizontal plane at the top of the main rail, a 100 tapering guide secured to the seat between the sides thereof, a lever pivoted to the seat between the sides, and forming a continuation of the tapering guide, a pin secured to the lever and disposed in the last-mentioned 105 slot, and an arm secured to the rock shaft, and articulated to the last-mentioned pin, 110

a lever adapted to be carried by a car, a wheel mounted to rotate on the lever which may be moved by the lever at either side of the tapering guide, to contact with the side 5 of the lever at the adjacent side of the second-mentioned seat to move the lever from the said side of the seat.

In testimony whereof I have signed my name to this specification in the presence of two subscribing witnesses.

ARTHUR COULOMBE.

Witnesses:

J. OSCAR FAUPINE,
JOSEPH N. HAMEL.
